UNITED STATES PATENT OFFICE.

GEORGE S. LEWIS, OF SPRINGFIELD, MASSACHUSETTS, ASSIGNOR TO J. STEVENS ARMS & TOOL COMPANY, OF CHICOPEE FALLS, MASSACHUSETTS, A CORPORATION OF MASSACHUSETTS.

FIREARM.

1,136,247.

Specification of Letters Patent.

Patented Apr. 20, 1915.

Application filed January 15, 1915. Serial No. 2,296.

To all whom it may concern:

Be it known that I, GEORGE S. LEWIS, a citizen of the United States, and a resident of Springfield, in the county of Hampden, 5 in the State of Massachusetts, have invented certain new and useful Improvements in Firearms, of which the following is a specification, reference being had to the accompanying drawings, forming a part hereof.

10 This invention relates to firearms of low cost and is concerned particularly with double barreled breech loading shot guns.

The invention has for its principal object to improve generally guns of this type by 15 simplifying the construction thereof, reducing the machine work to a minimum, rendering the coöperating elements of the various mechanisms more positive and invariable in their actions and otherwise increasing the 20 efficiency and reducing the cost of manufacture of these guns.

In accordance with the invention, the frame, breech, and tang are cast in one piece and are chambered so as to permit the ready 25 mounting therein of the required firing and controlling mechanism, and special provision is made for the placing of the firing pins and their main springs.

Another feature of the invention is concerned with the provision of an extractor 30 which is actuated positively upon the breaking of the gun and is subsequently restored positively to retracted position upon the subsequent closing of the breech. The improved extractor has coöperating therewith certain devices which, while insuring its usual operation so long as the gun is assembled, will automatically permit the extractor to remain inactive when the parts of 35 the gun are disassembled. The last named devices may also serve to disconnect automatically the cocking lever from its actuating member.

The improved gun also embodies certain 40 features of construction concerning the sears, the safety button, etc., by which a more compact and efficient structure is insured than has been possible in similar firearms now known.

45 Reference is now to be had to the accompanying drawings for a detailed description of the invention, in which—

Figure 1 is a side view of a double barreled shot gun embodying the present invention. Fig. 2 is a fragmentary view on a somewhat larger scale, partly in side ele-

vation and partly in section, of the gun shown in Fig. 1, parts being broken away to show the relative arrangement of the firing and controlling devices. Fig. 3 is a fragmentary view somewhat similar to Fig. 2 but showing the gun in a "broken" position, for the ejection of shells. Fig. 4 is a view in section taken on the plane indicated by the line 4—4 of Fig. 3 and looking in the direction of the arrows. Fig. 5 is a fragmentary view in section taken on the plane indicated by the line 5—5 of Fig. 3 and showing in detail the improved safety button. Fig. 6 is a view in perspective of the single casting embodying the frame, breech and the tang of the improved gun. Fig. 7 is a fragmentary view in which are indicated the barrel and frame of the improved gun just before they are completely disassembled, the fore-end having been previously removed. Fig. 8 is a detail view in perspective of the improved abutment for the firing pins and their main springs. Fig. 9 is a detail view in perspective of the supporting post for the abutment shown in Fig. 8. Fig. 10 is a detail view in perspective of the improved safety button.

The gun in which the present improvements are embodied is of the hammerless type and comprises generally a stock *a* to 85 which is affixed a frame *b* on which are pivotally supported the barrels *c*, as through a pivot pin *b'*, the barrels being maintained in fixed relationship to the frame *b* by the usual fore-end *d* and top lever *e*.

Referring particularly to Fig. 6, it will be evident that the frame *b* is cast integral with the breech *b²* and the tang *b³*, the latter comprising generally a hollow frame extending 95 rearwardly from the breech and being open in its sides to permit the firing and controlling devices to be readily mounted therein. The skeleton character of the casting shown in Fig. 6 and the accessibility to the chamber formed therein makes it unnecessary to machine the interior before mounting the mechanism to be later described. The casting in its rough state will, of course, be finished at the exposed places and along such 100 surfaces as are intended to have snug engagement with coöperating parts, such as the front wall of the breech *b²* and the upper face of the frame *b*, but aside from these 105 finishing operations, the casting can be immediately drilled to receive the supporting pins for the various devices which are to be

mounted therein. For instance, in the improved firearm, the wall of the breech b^2 is drilled through, as at b^4 , to receive the respective firing pins f which may be formed integral with the plungers f' on which are secured abutments f^2 for the respective main springs g . These main springs g are seated on a yoke h , the web of which is slotted, as at h' , to receive loosely the plungers f' . The yoke h may conveniently be mounted in the wall of the frame by placing it in position and then passing a pin i through holes b^5 formed in the wall of the frame and holes h^2 drilled in the arms of the yoke. Obviously, the pressure of the main springs g has a tendency to rock the yoke h about its supporting pin i and it is therefore necessary to counteract this tendency by mounting a post k in the frame b to the rear of the yoke h and in such position that the web of the yoke seats on a shoulder k' with which the post is provided. The post k may conveniently be placed in the slot b^6 which is formed to receive the triggers l and may be fastened in position by means of a pin m passed through holes b^7 drilled in the frame b and through a registering hole k^2 drilled in the post k .

To the rear of the post k are mounted the usual triggers l with which coöperate respectively sears n , each of which is formed with an arm n' for coöperation with the respective trigger, and a hook n^2 for the retention of the respective plunger f' in retracted position, each plunger being formed at its rear end with a notch f^3 for engagement by the said hook. The sears n are mounted on a common pivot pin o which may be passed through the sears and through holes b^8 drilled in the tang b^3 at the rear end thereof. On the same pin o and between the sears n is pivotally mounted the swinging safety latch p at the lower end and on the opposite faces of which are formed lateral pins p' arranged to be swung in the path of the respective triggers l and prevent movement thereof for the purpose of firing the gun. The upper end of the latch p is engaged by a reciprocable safety button q , one side of which is formed with a slot q' , the bottom of which is reversely beveled, as at q^2 , to coöperate with a spring-pressed keeper r . The safety button q is engaged by the usual locking bolt e' , the movement of which is initiated by the top lever e , the locking bolt serving to force the safety button q to safety position whenever the gun is broken for reloading, this movement of the safety button, of course, serving to swing the pins p' of the safety latch p in the path of the triggers l . This condition is maintained until the safety button q is manually slid to firing position, whereupon the pins p' are swung out of the path of the triggers l and the latter can then be actuated to rock the sears n about their pivotal support o and dis-

engage the hooks n^2 from the notches f^3 , thereby permitting the main springs g to force the respective firing pins into contact with the appropriate shell and explode the same in the usual manner.

70

The gun is cocked by the devices now to be described. The barrels c have slidably mounted on their lower faces, adjacent their rear ends, a cocking member s which may be supported by a transverse pin c' carried in a downward extension c^2 of the barrels and resting in a slot s' of the member s , and by a longitudinal pin s^2 which is formed on the end of the cocking member s and rests in said extension c^2 . The cocking member s has a notch s^3 in which the noses t of cocking levers t' rest so long as the parts of the gun are assembled, the tails t^2 of the cocking levers being disposed operatively in the path of the respective abutments f^2 on the firing pins f . From this description, it will be evident that when the gun is broken by actuation of the top lever e , in the usual manner, the cocking member s is carried by the barrel c and tends to move with respect to the cocking levers t' , the engagement of the noses t of these levers with the notch s^3 , however, serving to rock the levers about their supporting pin t^3 and thereby press the tails t^2 of the levers into operative engagement with the abutments f^2 , respectively, and retract the firing pins f against the action of the respective main springs g . This retraction of the pins f continues until the notches f^3 at their rear ends are engaged respectively by the hooks n^2 of the respective spring-pressed sears n . When the barrel is later returned to normal position with respect to the frame b and the breech b^2 , the firing pins f are in position for firing although, as pointed out before, the piece cannot be fired until the safety button q is slid to firing position.

It is obvious that in cocking the gun in the manner just described, the tendency is for the cocking member s to be slid longitudinally under the pressure exerted thereon by the noses t of the cocking levers t' and, accordingly, it is necessary to make adequate provision for the counteraction of this tendency. In the illustrated embodiment, the cocking member s is formed on its upper side with a lug s^4 which engages a short plunger rod u , the end of which is beveled, as at u' , and engaged by a spring-pressed abutment d' which is mounted in the rear end of the fore-end d and coöperates with the pivot pin b' for maintaining the barrels c in pivotal engagement with the frame b . So long as the fore-end d is in its normal position along the underside of the barrels c , the end of the abutment d' rests against the beveled face u' of the plunger u and thereby maintains the latter in its innermost position and holds it with the cocking member s against

longitudinal movement under pressure of the cocking levers t' , in the manner referred to. If, however, the fore-end d with the abutment d' be removed and the gun be held 5 with the barrel pointing downward, as would be most natural and as is illustrated in Fig. 7, the cocking member s will slide, under the influence of gravity, in a longitudinal direction, until the notch s^2 is 10 out of engagement with the noses t of the cocking levers t' . If the piece is then broken, the cocking member s will move past the noses t of the cocking levers t' , as indicated in Fig. 7, and the barrels 15 will be readily disassembled from the frame b without causing the gun to be cocked. Advantage is taken of the cocking devices just described to provide in combination therewith a simple and efficient 20 extractor operable positively. The extractor is indicated generally at v and is shown as formed with a cylindrical extension v' of the same general form as the plunger u and mounted slidably in the lower face of the 25 barrels c and in alignment with the said plunger. The underside of the cylindrical body v' of the extractor v is notched, as at v^2 , to receive a lug s^3 formed on the cocking member s , the outward movement of the 30 extractor being limited by the lug s^3 . Movement of the extractor is caused by the abutment of the plunger rod u against the end of the cylindrical body v' of the extractor and the longitudinal movement of the plunger 35 rod u through the co-operation of its beveled end u' with the abutment d' of the fore-end d during the breaking of the gun.

It will be evident by reference to Figs. 2 and 3 that as the barrels c move about 40 the pivot pin b' , relative movement between the plunger rod u and the stationary abutment d' will cause the plunger u to move rearwardly and actuate the extractor v positively. This rearward movement of the 45 plunger u does not of course, interfere with the function of the cocking member s but, on the contrary, causes a like rearward movement of the cocking member to compensate for its arcuate movement. As noted 50 before, when the fore-end d is removed, as shown in Fig. 7, and the plunger rod u is permitted to slide freely under the influence of gravity, the barrels c can be removed readily from the frame b and without actuation of either the cocking levers t' or the extractor v .

From the somewhat detailed description given of the character of the casting shown in Fig. 6 and the means for and method of 55 mounting the firing and controlling mechanism in the casting, the great saving in the cost of manufacture of the improved gun and the simplicity of construction and the

consequent efficiency of operation of the operating parts, will be appreciated. 65

While most of the features of the gun are concerned with improvements of known parts, it is to be understood that certain of the elements are a radical departure from those hitherto employed and perform functions which are novel in character. The scope of the invention with respect to these novel elements and the new features of those devices which are improved, are pointed out in the appended claims, and the substitution 70 of mechanical equivalents for these novel elements and the rearrangement of parts or mere change in mechanical form of the improved devices, are to be deemed within the spirit of this invention. 75

I claim as my invention:

1. In a double barreled gun, triggers, sears therefor, a common pivot pin on which the sears are carried, and a safety latch carried pivotally on said pin. 80

2. In a firearm, a chambered frame, plunger, firing pins carried thereby, main springs therefor, a fixed abutment for the main springs comprising a yoke mounted in the chamber and a post engaging the yoke 90 to hold the same against movement, and a pin passed through the walls of the chamber and the arms of the yoke to support the same. 85

3. In a double barreled gun, triggers, sears 95 therefor, a common pivot pin on which the sears are carried, and a safety latch carried pivotally on said pin and disposed between the sears.

4. In a double barreled gun, triggers, sears 100 therefor, a common pivot pin on which the sears are carried, and a safety latch carried pivotally on said pin and disposed between the sears, the safety latch being provided at its lower end and on opposite faces with 105 pins to lock the triggers respectively.

5. In a firearm, the combination with the barrel and fore-end, of a cocking member and extractor carried slidably by the barrel, a plunger carried slidably by the barrel and 110 adapted to move the cocking member and the extractor positively in one direction, an abutment carried by the fore-end and co-operating with the plunger to cause sliding movement thereof when the gun is broken, 115 the plunger with the cocking member being freely slidable with respect to the extractor to inoperative positions whenever the fore-end is removed.

This specification signed and witnessed 120 this 6th day of January A. D. 1915.

GEORGE S. LEWIS.
